INVENTOR

WILLIAM NAIDA.

BY

Richard B. Devon

ATTORNEY.

UNITED STATES PATENT OFFICE.

WILLIAM NAIDA, OF PATERSON, NEW JERSEY.

COLLAR BUTTON.

Application filed January 25, 1924. Serial No. 688,532.

To all whom it may concern:

Be it known that I, WILLIAM NAIDA, a citizen of the United States, residing at Paterson, in the county of Passaic and State 5 of New Jersey, have invented certain new and useful Improvements in Collar Buttons, of which the following is a specification.

This invention relates to collar buttons and more particularly to a novel and improved means for retaining a collar button to the shirt band so as to prevent its loss.

One of the objects of my invention is to provide a collar button and particularly the shank thereof with a pair of wings or tongues extending outwardly thereof so that when the collar button is positioned and rotated a quarter turn, it may be thus secured to the shirt band.

Another object of my invention is to provide a collar button of the above character wherein the back and wings or tongues may be secured and assembled with the shank of the button in one operation.

To enable others skilled in the art to fully comprehend the underlying features of my invention that they may embody the same in the various modifications in structure and relation contemplated, drawings depicting a preferred form have been annexed as a part 30 of this disclosure and in such drawings, similar reference characters denote corresponding parts throughout all the views, of which,

Figure 1 is a front view showing the collar button in the buttonhole of a shirt band.

Figure 2 is a side view showing the collar button, the shirt band being shown in section.

Figure 3 is a sectional view showing the assembly of the collar button.

Figure 4 is a view of the blank, the shank being shown in section.

Referring now to the drawings wherein like reference characters designate corresponding parts throughout the several views, 45 5 designates the shank and 6 the head of the conventional type of collar button, said shank being provided with a reduced end 7 which may be riveted or stamped to the

annular back 8. My invention proper comprises and is formed of a substantially rectangular blank 9, having rounded ends 10, which blank is formed with a depression 10 of a diameter to receive the shank 5 above referred to. The reduced portion 7 of the shank extends through an aperture in the depression 10 so that the back 8, shank 5 and the wings or tongues 9 may be assembled and formed in one operation. In practice, the tongues or wings 9 are slightly curved, being substantially the width of the back 8 so that the said wings may be passed through the buttonhole 11 and when the shank is given a quarter turn, the collar button will be secured to the shirt band in the manner well understood. If so desired, 65 the shank may be secured to the back 8 in any other manner as manufacturing necessities may require, my invention being limited to the form and arrangement of the tongues or wings 9, mounted on the shank in spaced 70 relation to the top face of the back 8, thus permitting the inner fold 11 of the neck band to lie beneath the tongues.

While I have illustrated and described my invention with some degree of particularity, 75 I realize that in practice various alterations therein may be made. I therefore reserve the right and privilege of changing the form of the details of construction or otherwise altering the arrangement of the correlated 80 parts without departing from the spirit of the invention or the scope of the appended claim.

Having thus described my invention, what I claim as new and desire to secure by 85 United States Letters Patent is:—

A collar button comprising a shank having a head and back at each end thereof, said shank being reduced at one end thereof, a blank formed with a central depression and 90 outwardly extending wings spaced from the back, said reduced portion of the shank extending through an aperture in the central depression.

In testimony whereof I affix my signature.

WILLIAM NAIDA. [L.S.]
